UNITED STATES PATENT OFFICE.

EDGAR F. CROWTHER, OF VICKSBURG, MISSISSIPPI.

DEVICE FOR ASSEMBLING THE ROLLERS OF ROLLER-BEARINGS.

SPECIFICATION forming part of Letters Patent No. 700,178, dated May 20, 1902.

Application filed August 22, 1901. Serial No. 72,915. (No model.)

To all whom it may concern:

Be it known that I, EDGAR F. CROWTHER, a citizen of the United States, residing at Vicksburg, in the county of Warren and State of Mississippi, have invented new and useful Improvements in Devices for Assembling the Rollers of Roller-Bearings, of which the following is a specification.

The main object of my invention is to provide a device for assembling the rollers of roller-bearings which in operation shall enable the rollers and wear-plates, if such be used, to be readily and expeditiously placed about the axle and to be held in position while the box-sections are secured in place about the rollers.

Other objects of the invention relate to details of construction and to combinations and arrangements of parts, all as hereinafter described, and particularly pointed out in the claims.

In order that my invention may be fully understood, I have illustrated the same in the accompanying drawings, in which—

Figure 1 is an end elevation of the device, showing by dotted lines one part of the frame swung away from the other. Fig. 2 is a side elevation of the device. Fig. 3 shows in enlarged detached views, partly in section and partly in elevation, portions of the two heads of the device. Fig. 4 is a section through an axle surrounded by rollers and showing the box-sections as about to be applied thereto. Fig. 5 is a detail view of a modified construction of spring-pin. Fig. 6 is an end elevation on a reduced scale, showing a modification in the manner of connecting the two halves of the device; and Fig. 7 is a view in elevation, partly broken away, showing the modified form of spring-pin combined with the apparatus.

Referring to the drawings, 1 2 indicate, respectively, the two circular heads of the device, each of which is formed in two halves 3 4, provided with a semicircular recess 5, so that when the two halves of each head are brought together they will provide a circular opening 6, the openings 6 in the two heads being in alinement and adapted to receive the axle 7, about which the rollers are to be arranged. The two halves of each head are

hinged together at one side at corresponding points, as indicated at 8, and are provided with shoulders 8^a to prevent them being swung unnecessarily far apart. When brought together, the two halves of each head are secured by means of a spring-catch 9.

The head 1 comprises a plate 10, having an annular flange 11, which projects some distance outward from and at right angles to said plate 10. Said plate is provided with a series of apertures 12, arranged in one or more circular series around the plate 10, through each one of which projects the end of a pointed pin 13, having a collar 14, adapted to bear against the plate 10. Surrounding each of the pins 13 is a coiled spring 15, bearing at one end against the collar 14. Projecting outward from the edge of the annular flange 11 at four or more points are fixed pins 16, provided with screw-threaded portions 17 adjacent to the flange.

The numeral 18 indicates a cover for the head 1, which is provided with apertures 19, corresponding to the apertures 12 of the plate 10. Said plate is also provided with suitable apertures to pass over the fixed pins 16 and is held against the edge of the flanges 11 by means of nuts 20, screwed on the screw-threaded portions 17. When so positioned, the rear ends of the pins 13 will project through the apertures 19 and the cover 18 will bear against the outer ends of the springs 15. For ease in description I have referred to the "plate" 10 and "cover" 18; but it will of course be understood that each of these parts consists of two semicircular sections, forming, when corresponding sections are connected together by the pins 16 and nuts 20, the two halves of the head 1, as previously described. The two sections of the plate 10 are also each provided with two or more screw-threaded apertures, in each of which engages a screw-threaded portion of a relatively long thumb-screw 21, passed through the cover 18 and, in common with the pins 13, having a pointed end. Each section of the head 2 is provided with a series of fixed pins 22, which when the sections are brought together, as shown by the full lines in Fig. 1, are adapted to align with the pins 13. The parts of head 2 are also provided with pointed thumb-screws 23,

corresponding to and adapted to aline with the similar screws 21. The heads 1 and 2 are connected together by means of side bars 24, one of which is carried by each section of the head 1 and, extending inward toward the head 2, has its end passed through an opening in a boss 25, one of which is formed at the side of each half or section of the head 2 and is adjustably held in said opening by means of a set-screw 26. Each of the side bars 24 is provided with a shoulder 27 to limit the inward movement of the head 2, and the outer ends of said bars are provided with stops, pins, or the like 28 to prevent the head 2 from sliding off of said bars.

The manner of using the device is as follows: By means of the set-screws 26 the head 2 is first secured at the required distance from the head 1. The frame as a whole is now opened upon the hinges 8 and the rollers 29 arranged in each section. This is done by placing one end of a roller against the point of a pin 13 and pressing said pin inward against the resistance of its spring until the opposite end of the roller may be brought to bear against the point of the corresponding pin 22, when the pressure of the spring 15 will hold the roller in place. Preferably, however, the ends of the rollers are provided with small recesses to receive the pointed ends of the pins 13 and 22. In like manner other rollers are secured in position to form in each section of the frame a semicircular series of rollers. As shown by Fig. 1, two circular series of rollers may be secured in the frame if a double set of rollers is to be employed in the bearing, as shown in Fig. 4. The rollers having been fixed on the pins in the frame, as described, if wear-plates, such as 30, are to be used in the bearing such wear-plates in half or quarter sections are secured about the rollers 29 by screwing the pointed ends of the thumb-screws 21 23 into engagement with the end edges of said wear-plates. The frame is now placed over the axle 7 and its two parts brought together, so that the opening 6 shall encircle the axle. The spring-catches 9 will hold the two parts of the frame closed. The two box-sections 31 are now placed in position to have their recesses encircle the wear-plates and rollers and are properly secured together in the ordinary manner. The wear-plates and rollers will now be held by the boxes in their proper position and my device may be removed. This is done by loosening the set-screws 26 and moving the head 2 in a direction away from the head 1, so as to release the pressure of the springs 15, and then unfastening the catches 9, when the two parts of the frame may be swung apart and removed from about the axle.

In Fig. 5 I have shown a modification in the character of the spring-pins. In this instance instead of having a separate pin and spring I provide a coiled spring 32 with a projecting

pointed portion 33, which is non-circular in cross-section and passes through a correspondingly-shaped aperture 34 in the plate 10. The opposite end portion 35 of the spring is screw-threaded and is screwed into the cover 18. The non-circular part 33 will prevent the spring from unscrewing. The operation will be apparent and need not be described further than to state that the coil of the spring bearing against the plate 10 serves to limit the outward movement of the pin 33 in the same manner as the collar 14 of the previous construction. The fixed pins 16 serve as legs, upon which the device may be set when not in use.

In Fig. 6 I have shown the device as adapted to be inserted endwise over the axle, the two halves of each head being slidably mounted with relation to each other instead of having a hinge connection, as in the previous construction. To this end one of the halves 3 of each head has projecting from its inner edge at opposite ends, respectively, two pins 36. The other half 4 is suitably apertured at opposite ends to slide over these pins and provided with spring-catches or other fastening means 37 for holding the two halves together. After the half 4 has been mounted on the pins 36 nuts 38 are screwed on the outer ends of said pins to prevent the part 4 from sliding off of said pins. In opening or closing the device the part 4 is moved from or toward the part 3, sliding over the pins 36, and in placing the rollers in position around the axle the device is inserted endwise over the axle. In other respects the operation is the same as with the construction shown in Fig. 1.

Having thus fully described my invention, what I claim as new is—

1. A device for the purpose described comprising two connected heads, each of which is made in two separable parts having a central recess and provided with inward-extending pins, and means for adjusting one of said heads toward and from the other.

2. A device for the purpose described comprising two connected heads, each of which is made in two separable parts having a central recess and provided with inward-extending pins, the pins on one head being yielding.

3. A device for the purpose described comprising two connected heads, each of which is made in two separable parts having a central recess and provided with inward-extending pins, the pins on one head being yielding, and means for adjusting one of said heads toward and from the other.

4. A device for the purpose described comprising two connected heads, each of which is made in two separable parts having a central recess and provided with inward-extending pins, the pins on one head being yielding, and a series of pointed thumb-screws carried by each head.

5. A device for the purpose described comprising two connected heads, each of which is

made in two separable parts having a central recess and provided with means for detachably engaging a series of rollers.

6. A device for the purpose described comprising two connected heads, each of which is made in two recessed parts having a hinge connection and provided with means for detachably engaging a series of rollers.

7. A device for the purpose described comprising two connected heads each of which is made in two separable parts having a central recess, one of said heads carrying a series of stationary pins and the other of said heads comprising connected parallel plates having a series of spring-controlled pins mounted therein.

8. A device for the purpose described comprising two connected heads each of which is made in two separable parts having a central recess, one of said heads carrying a series of stationary pins and pointed thumb-screws and the other of said heads comprising connected parallel plates having a series of spring-controlled pins and a series of pointed thumb-screws mounted therein.

9. A device for the purpose described comprising two heads each of which is made in two separable parts having a central recess, a series of inward-extending pins carried by each of said heads, one of said heads being provided on opposite sides with apertures, bars connected at one end to opposite sides of the other head and having their opposite ends passed through said apertures, and set-

screws for engaging such ends, whereby one 35 of said heads may be adjusted toward and from the other.

10. A device for the purpose described comprising two connected heads each of which is made in two separable parts, one of said heads 40 carrying a series of stationary pins and the other of said heads comprising a flanged plate having screw-threaded pins extending outward from its flange, a cover-plate resting on said flange and apertured to pass over said 45 pins, nuts on said pins for securing the cover-plate in place, and a series of spring-controlled pins mounted in said plates, the combination operating as set forth.

11. In a device for the purpose described, 50 the combination with the head 2 carrying the fixed pins, the head 1 comprising connected parallel plates having screw-threaded and non-circular apertures, respectively, and a coiled spring located between said plates and 55 having at one end a screw-threaded projection engaging in said screw-threaded aperture and at its opposite end a pointed non-circular projection extending through said non-circular aperture, substantially as de- 60 scribed.

In testimony whereof I have hereunto set my hand in presence of two subscribing witnesses.
